CLAIM

We claim the ornamental design for an attachment nozzle for a handheld hair styling device, as shown and described.

DESCRIPTION

FIG. 1 is a front perspective view of an attachment nozzle for a handheld hair styling device showing our new design; FIG. 2 is a front view thereof; FIG. 3 is a rear view thereof; FIG. 4 is a side view thereof; FIG. 5 is a side view of the opposite side of FIG. 4; FIG. 6 is a top view thereof; and, FIG. 7 is a bottom view thereof.

(Continued)

The broken lines shown in the drawings illustrate portions of an attachment nozzle for a handheld hair styling device that form no part of the claimed design.
